UNITED STATES PATENT OFFICE.

JACOB FRANZ, OF ERIE, PENNSYLVANIA.

LEVELING DEVICE.

Application filed April 1, 1920. Serial No. 370,409.

To all whom it may concern:

Be it known that I, JACOB FRANZ, a citizen of the United States, residing at Erie, in the county of Erie and State of Pennsylvania, have invented new and useful Improvements in a Leveling Device, of which the following is a specification.

The object of this invention is to level different points, particularly such points as have intervening obstructions.

The invention is illustrated in the accompanying drawings as follows:—

Fig. 1 shows an elevation of the device.

Fig. 2 a central section of one of the ends.

Fig. 3 a plan view of the transparent end tube.

1 indicates a flexible tube. This may be of any desired length. 2 indicates transparent tubes connected with the ends of the flexible tube. Scales 3 are provided on the transparent tubes so as to facilitate the observation of a contained liquid A in the tubes.

Devices of this character have been heretofore used but the difficulty with such devices has been that when the transparent tube at one end has been accidentally depressed below the other transparent tube a part of the liquid was discharged so that constant care had to be encountered in maintaining the transparent tubes at approximately the same level. With the present device an automatic valve is provided which prevents the discharge of the liquid and is

preferably so arranged as to allow the air 35 to have free egress and ingress to and from the tube so that there may be no differences in air pressure on the liquid. This is accomplished by the following devices:—A tip 4 is arranged at the end of each transparent tube. The tip has a discharge air opening 5 leading to it and a valve seat 6 on the inner surface of the tip surrounding the opening 5. A ball check 7 preferably in the form of a float valve is 40 adapted to close the opening 5 when subjected to the action of the liquid either by the rising of the liquid in the transparent tube or by a flow of the liquid with a depression of the tube.

The valve seat in the upper end of the tube 2 is provided with grooves 8 in order to maintain communication between the interior of the tube and the atmosphere when the ball float 7 rests on the valve seat.

What I claim as new is:—

In a leveling device, a flexible tube; a transparent tube at each end of the flexible tube; a valve on each of the transparent tubes comprising a case with a valve seat 60 at the outer discharge side of the case; a ball float operating on the seat, the surface of the float seating directly on the valve seat; and means preventing the float from forming a closure excluding the air.

In testimony whereof I have hereunto set my hand.

JACOB FRANZ.
